CONTAINER CLOSING DEVICES

Harold K. Deanisson, Merchantville, N. J., and George Dresch, Parkland, Pa.; said Dresch assignor to said Deanisson.

Application July 5, 1955; Serial No. 519,758

61 Claims. (Cl. 1—106)

The invention relates to container closing devices, and more particularly to container closing devices which gather and bind the tops of bag containers.

Heretofore devices have been employed for binding the tops of bag containers. These devices, however, have been highly complex in structure and operation, making them expensive to manufacture and to maintain in operation. The very nature of these devices also makes them inefficient and unsatisfactory for operation at a high production rate.

Therefore, a principal object of the invention is to provide a new and improved container closing device which is inexpensive to manufacture and is highly efficient in operation.

Another object of the invention is to provide a new and improved container closing device which is simple in construction and operation.

Still another object of the invention is to provide a new and improved container closing device which is readily and inexpensively maintained in operation.

Yet another object of the invention is to provide a new and improved container closing device which is easily and inexpensively manufactured on a small or large scale basis.

A further object of the invention is to provide a new and improved container closing device which is designed for continuous operation over a long period of time without requiring replacement of its parts.

Still a further object of the invention is to provide a new and improved container closing device treating and closing containers at a high rate.

Yet a further object of the invention is to provide a new and improved container closing device which is fully automatic in operation.

Another object of the invention is to provide a new and improved container closing device utilizing electrical control and synchronizing apparatus.

Still another object of the invention is to provide a new and improved container closing device which is responsive to the container being treated.

Yet another object of the invention is to provide a new and improved container closing device performing successively gathering and binding operations and determining the completion of the gathering operation by the sensing of the treated container unit.

A further object of the invention is to provide a new and improved container closing device which allows the performance of a binding operation upon a treated container only after the completion of the gathering operation.

Still a further object of the invention is to provide a new and improved container closing device utilizing a standard stitching head which easily may be removed and replaced.

Yet a further object of the invention is to provide a new and improved container closing device which minimizes damage of the treated container unit.

Another object of the invention is to provide a new and

improved container closing device which is especially adapted for treating plastic-type container units.

Still another object of the invention is to provide a new and improved container closing device which can convey 5 a container unit by engaging its top end which end is also to be treated by the device.

Yet another object of the invention is to provide a new and improved container closing device which allows continuous operation of its conveying means.

10 A further object of the invention is to provide a new and improved container closing device which may operate satisfactorily over a wide range of conveying speeds.

Still a further object of the invention is to provide a new and improved container closing device which is especially 15 adapted for assembly line techniques.

Yet a further object of the invention is to provide a new and improved container closing device which is especially adapted for use with standard conveyor systems.

Another object of the invention is to provide a new and improved container closing device which readily may 20 be synchronized with auxiliary equipment.

Still another object of the invention is to provide a new and improved container closing device which is adapted for use with various size containers and auxiliary 25 equipment.

Yet another object of the invention is to provide a new and improved container closing device which is compact in size and can be readily moved and transported.

The above as well as many other objects of the invention are achieved by providing a container closing device 30 comprising container conveying means, container sensing means, container retaining means and container binding means.

35 The container conveying means comprises a pair of endless belts and a pressure plate. The endless belts travel along a predetermined conveying path and have vertical surfaces adapted to frictionally engage the first side of the top end of a bag container. The pressure plate extends along the conveying path and has a vertical surface proximate the vertical container engaging surfaces of the endless belts for slidably engaging the second side of the top end of the container. The pressure plate urges the first side of the container against the vertical surfaces of the endless belts, thereby increasing the frictional force applied to the container by the conveyor belts for directing it along the predetermined path.

40 The sensing means comprises a normally closed switch unit having an extended lever for engaging the container along the conveying path. The circuit of the switch unit is opened when the leading edge of a container engages its lever, and is closed when the lever loses contact with the container at its trailing edge.

45 The retaining means comprises a rod element which is extendable across the path of the container at a location following the switch unit of the sensing means, a relay unit, and a solenoid. The relay unit when in its set position energizes the solenoid, and de-energizes the solenoid when it is reset. The solenoid retracts the rod element when energized and allows the rod element to extend across the path when de-energized.

50 As the container unit moves along the path, its leading edge contacts the lever of the sensing means and opens the sensing switch circuit. This resets the relay and de-energizes the retaining means solenoid which extends the rod element. The extended rod element of the retaining means engages the leading edge of the container unit and prevents its motion past a binding location. The continuous action of the endless belts of the conveying means causes the top end of the container unit to be gathered at said binding location (when the rod element is extended) by urging the trailing edge of the container towards its leading edge.

The securing means comprises a stitching machine having a head positioned along the path for enclosing the gathered end of a container at the binding location.

Since the lever of the sensing switch is positioned proximate the binding location, it loses contact with the container unit at its trailing edge as the gathering operation is completed. The closing of the sensing switch at this time causes the securing means to bind the gathered end of the container unit which is retained at the binding location. The actuation of the securing means also sets the relay unit which results in the energization of the retaining means solenoid and the retraction of the rod element. This allows the container unit to proceed along its path out of the device after completion of the closing operation.

The above objects, as well as many other objects of the invention will become evident to those skilled in the art, when the following description of the invention is read in conjunction with the drawings, in which:

Figure 1 is a side elevational view of a closure device embodying the invention with a portion of the main frame unit broken away,

Figure 2 is an elevational view of the top portion of the container closing device taken in the direction of the lines 2, 2 of Figure 3,

Figure 3 is a sectional view taken along the line 3-3 of Figure 1,

Figure 5 is an enlarged detail view of a portion of Figure 4 illustrating the container conveying, sensing, and retaining means upon completion of a closing operation,

Figure 6 is a view similar to that of Figure 5 illustrating a container unit engaging the lever of the sensing switch and just contacting the extended rod element of the retaining means at its leading edge,

Figure 7 is a view similar to that of Figure 5 illustrating a gathered container unit positioned at the binding location by the extending rod of the retaining means and being bound by the stitching machine of the securing means,

Figure 8 is a sectional view taken along the line 8-8 of Figure 5 illustrating the conveying means engaging the upper flattened end of a container unit.

Figure 9 is an enlarged detail view of a portion of the closing device taken along the line 9-9 of Figure 1,

Figure 10 is a detail view taken along the line 10-10 of Figure 5,

Figure 11 is a detail view taken along the line 11-11 of Figure 5 showing the rod element of the retaining means.

Figure 12 is a plan view illustrating in detail the stitching machine of the securing means with its cam wheel engaging the set-up switch,

Figure 13 illustrates the top of a bag container unit which has been gathered and bound by the container closing device,

Figure 14 is a schematic diagram illustrating the electrical system of the container closing device before its on-off switch is closed,

Figure 14a is the diagram of Figure 14 illustrating the electrical system with its on-off switch closed and the first workless stapling operation completed,

Figure 14b is the diagram of Figure 14 illustrating the electrical system when a container unit is engaging its sensing switch element, and

Figure 15 is a side elevational view of a modified form of container closing device including an auxiliary conveying means for supporting the bottom portion of a container which is synchronously driven with the top engaging and conveying means.

Like numerals designate like parts throughout the several views.

Refer now to the figures for a description in greater detail of a container closing device embodying the invention. The Figure 1 shows a container closing device which has a main frame unit 19 comprising a base 20, and a verti-

cal I-beam member 22. The member 22 has its lower end connected near the edge of the base 20 and its upper end joined with a horizontal top plate 24. A portion of the top plate 24 extends over the base 20 and is provided with an opening therethrough.

A positioning screw 28 has its actuating wheel 26 supported by the top plate 24, while its screw portion 30 is received through the opening of the top plate 24 and extends vertically along the I-beam member 22.

10 An adjustable block member 32 has a central portion 33 threadedly engaging the screw portion 30 of the positioning screw 28, and a pair of vertical flange portions 34 and 36. The flange portion 34 of the block member 32 connects with a guide plate 38 which bears against the flange 40 of the I-beam member 22. The guide plate 38 has a pair of clamping members 42 for controllably securing the guide plate 38 with the I-beam member 22 when bolts 43 are tightened.

In operation, the adjustable block member 32 may 20 be raised or lowered to a desired elevation by turning the positioning screw 28 in one direction or the other. When the block member 32 is at the desired elevation, the flange screws 43 may be tightened to lock the block member 32 in position and supportingly 25 secure it with the vertical I-beam 22 of the frame unit 19. Thus, the position of the block member 32 may be adjusted and changed from time to time as conditions require.

A mounting unit 44 has the vertical surface of its 30 end 46 bolted to the flange 36 of the adjustable block member 32, while the vertical surface of its other end 48 is secured with a bracket 50 which mounts an electric drive motor 52. The end 48 of the mounting unit 44 is provided with a downwardly extending elongated portion 54.

The wire stitcher head 56 of a securing means is secured with the portion 54 of the mounting unit 44, while its clincher block arm 58 is also supported by and extends downwardly from the mounting unit 44. 40 The lower end of the arm 58 is provided with a clincher block 60 which is positioned proximate the stitching head 56 and cooperates with it during a stitching operation.

The stitching head 56 receives power from the drive 45 motor 52 which is transmitted from the motor shaft to the drive shaft 59 of the stitching head 56 by a motor pulley drum 61 and a stitching head pulley wheel 62 which are linked by belts 64. The drive motor 52 continuously rotates the drive shaft 59 of the stitching head 50 56, although the clutch of the stitching head is engaged to actuate the head only during a stitching operation.

The stitching head 56 is supplied with wire from a 55 supply reel 68 and is actuated to perform a stitching operation by a clutch lever 70. The clutch lever 70 is connected by a link rod 72 with the actuator 73 of a solenoid 74 (see Figure 12). When the stitching head solenoid 74 is energized, the clutch lever 70 is actuated causing the head to perform a stitching operation.

The stitching head 56 is of the type which performs a 60 complete stitching operation once it is initiated by the actuation of its clutch lever 70. A stitching head of this type is described in U. S. Patent No. 2,554,691 issued to R. E. Zeruneith on May 29, 1951.

65 A cam wheel 76 is secured with the shaft 75 of the stitching head 56 which revolves only when the head is performing a stitching operation. In this particular case the cam wheel rotates and makes one complete revolution with each complete stitching operation of the head 56.

70 A set-up switch 78 is provided with an actuating lever which engages the cam wheel 76 of the stitching head 56. The set-up switch 78, which has two positions, is normally in its first position and momentarily assumes its second position during a stitching operation by the revolution 75 of the cam wheel 76. The set-up switch 78 reassumes its

first position upon the completion of the stitching operation.

The lower portion of the extension 54 of the mounting unit 44 supports a conveyor frame 80 of a container conveying means and has a main leg 82 which is bent at its forward end and is secured at its rear end with a second substantially perpendicular leg 84. The extending ends of the legs 82, 84 are connected by a band 86 to form a substantially triangular configuration.

A plurality of pairs of pillow boxes or bearing mounting units 88, 90, 92, 94 and 96 are connected with the conveyor frame 80. The bearing units 90 are joined with the leg 82 where it is bent, while bearing units 96 are hingedly secured intermediate the ends of the band 86 of the conveyor frame 80.

Each pair of bearing units 88, 90, 92, 94 and 96 rotatably supports the vertical shaft of a respective conveyor drums 98, 100, 102, 104 and 106. Each of the drums is provided with a pair of annular grooves 107 which respectively receive a pair of endless conveyor belts 108, 110 and determines their paths.

The conveyor belts 108, 110 have identical configurations with the belt 108 positioned vertically above the belt 110. The belts 108, 110 each have aligned vertical gripping surfaces 111.

The position of the bearing units 96 may be varied by a screw element 97 for adjusting the tension of the conveyor belts 108, 110.

The conveyor belts 108, 110 are moved in a clockwise direction about their idler drums 98, 100, 102 and 106 by the drive drum 104.

The shaft of the drive drum 104 is joined to a gear wheel 112 which is linked by a chain 114 with a gear wheel 116. The gear wheel 116 is connected by a rotatable shaft 118 with a speed reduction gear wheel 120 which is driven by a pinion gear wheel 122. The pinion wheel 122 is joined with the stitching head pulley 62 which in turn is coupled with the drive motor 52.

The driven shaft 118 is rotatably secured at its ends by pillow blocks or bearing units 124 and 126. The bearing unit 124 is secured to a horizontal band 128 which is attached between the mounting unit 44 and the drive motor 52, while the lower bearing unit 126 is joined to a bracing band 130 (Figure 3) which extends between the leg 82 and the connecting element 86 of the conveyor frame 80.

The container conveying path is substantially linear and extends between the idler drums 100 and 102 in the clockwise direction.

A back member 132 (Figure 8) is supported from the main element 82 of the conveyor frame 80 by a pair of brackets 134 and is positioned behind the conveyor belts 108, 110 along the conveying path between the idler drums 100 and 102. The back member 132 positively positions the conveyor belts 108, 110 by having a main portion which slidably engages their vertical back surfaces 134, and a central portion 136 which extends between the conveyor belts 108, 110 and maintains their vertical separation. The extending portion 136 of the back plate 132 also slidably engages the bottom surface 138 of the upper conveyor belt 108 to vertically support it under load condition.

A pressure plate 140 which is an elongated member has a main portion 142 with a vertical contact surface 144 (Figure 9), positioned proximate the vertical gripping surfaces 111 of the belts 108, 110 along the conveying path from the idler drum 100 to the extending arm 58 of the wire stitching machine. The forward portion 146 of the plate 140 is bent to form with the conveyor belts 108, 110 a converging entrance 148 to the container conveying path. The pressure plate 140 is supported in this position by a bracket 149 which extends from the leg portion 82 of the conveyor frame 80, and by the stitching machine arm 58 at its lower end.

When the conveying means is operating its conveyor belts 108, 110 are moving in the clockwise direction, so

that a container 150 may have its top end portion 152 introduced into the entrance 148. The container may be of the plastic bag type which is to be closed at its top end. The vertical surfaces 111 of the conveyor belts 108, 110 engage one side of the flattened end 152 of the container 150 between its leading and trailing edges 154 and 156, while its other side is slidably engaged by the vertical surface 144 of the pressure plate 140. The vertical surface 144 of the pressure plate 140 in slidably engaging one side of the top end 152 of the container 150, urges its other side against the gripping vertical surfaces 111 of the conveyor belts 108, 110 and increases the frictional gripping action of the belts for directing the container along the conveying path.

It also now may be noted that in operation, the backing plate 132 by affording additional backing support increases the gripping efficiency of the conveyor belts 108, 110 by allowing them to exert greater frictional forces upon the container 150. The backing plate 132 also vertically supports the upper conveyor belt 108 allowing it to carry the load of the container 150 without sagging. Since the belt 108 carries the main weight load of the container 150, the belt 110 acts mainly to direct the container 150 along the conveying path.

Container sensing means is provided which comprises a normally closed sensing switch element 162 secured to the lower end of the wire stitching arm 58 by a bracket 164 (see Figures 3 to 7 inclusive). The switch element 162 is provided with an actuating lever 166 which extends through a slot 168 in the pressure plate 142 for engaging the flattened end portion 152 of a container 150 between its leading and trailing edges 154, 156 as it proceeds along the conveying path. To assure positive action of the lever 166 of the switch element 162, it extends across the path intermediate the vertically positioned conveyor belts 108, 110. The central extending portion 138 of the backing plate 132 is limited in its extent to prevent its interference with the action of the switch lever 166, while the plate 132 continues at 170 along behind the belts 108, 110 to the stitching head 56.

The end of the actuating lever 166 of the switch element 162 is positioned along the conveyor belt preceding but proximate the clinching block 60 of the stitching arm 58.

When the flattened end portion 152 of the container 150 engages the lever 166 of the switch element 162 at its leading edge 154, the switch element 162 is actuated to its open position which it maintains until the lever element 166 loses contact with the container 150 at its trailing edge 156.

The guide box 174 of a container retaining means is received in the notched lower end of the stitching arm 58 at 172. The exposed side of the guide box 174 which is provided with a cover 176 slidably receives within it an extensible rod element 178.

The end 180 of the rod element 178 is secured to the actuated element 182 of a retaining means solenoid 184 which is mounted on the lower end of the guide plate 38. A pair of coiled springs 186 are connected between the guide box 174 and the activated element 182 of the solenoid 184 for urging the rod element 178 toward its extended position.

The other end 188 of the rod element 178 is slotted or forked to form upper and lower prongs 190 and 192.

A retaining means relay unit 160 when in its set position energizes the solenoid 184, and de-energizes the solenoid when it is reset.

When the solenoid 184 is energized, the rod element 178 assumes its retracted position with its prongs 190, 192 entirely within the guide box 174. When the solenoid is de-energized, the springs 186 move the rod element 178 into its extended position with the prongs 190, 192 projecting through the guide box 174 into the space between the upper and lower conveyor belts 108, 110. In extended position, the prong 190 and 192 of the rod ele-

ment 178 are respectively above and below the clinching block 60 of the securing means. The vertical plane of the container contacting surface 194 of the rod element 178 is also positioned to substantially bisect the horizontally extending arced surface of the clinching block 60.

In operation, as the flattened end 152 of a bag container 150 proceeds along the conveying path, the relay unit 160 is reset, retaining means solenoid 184 is de-energized and the rod element 178 is extended across the conveying path when the lever 166 of the sensing switch element 162 is actuated to its open position by contact with the container 150 at its leading edge 154 (see Figures 5 and 6). As the container 150 continues along the conveying path, its leading edge 154 engages the projecting prongs 190, 192 of the extended rod element 178 along its container contacting surface 194. The extended rod element 178 prevents the motion of the end portion 152 of the container 150 past its binding position which is at the clinching block 60. The continuous action of the conveyor belts 108, 110 urges the trailing edge portion 156 of the container 150 towards its leading edge 154 to effectively gather the top portion 152 at the binding location.

Since the end of the actuating arm 166 is proximate the clinching block 60 and the binding location, it loses contact with the container 150 at its trailing edge 156 just as the gathering operation is completed.

When the sensing element 162 returns to its closed position it energizes the securing means solenoid 74 which triggers the stitching head 56 causing it to perform a complete stitching operation by actuating its clutch lever 70.

Thus, the end 152 of the container 150 after it has been gathered and positioned at the binding location by the retaining means is operated upon by the staple driver bar 197 of the stitching head 56 in cooperation with the clinching block 60 to encircle and enclose the top end 152 of the container 150 with a metal band 196.

As the stitching head 56 performs its binding operation, the cam wheel 76 is revolved through a complete revolution of 360 degrees by its shaft 75. During the course of its rotation the cam wheel 76 actuates the extending lever of the set-up switch 78 momentarily causing it to assume its second position. The output signal developed by the set-up switch 78 in its second position sets the retaining means relay 160.

In its set position the relay unit 160 de-energizes the securing means solenoid 74 and energizes the retaining means solenoid 184. The de-energization of the securing means solenoid 74 releases the clutch lever and prevents the stitching head 56 from performing more than one complete binding operation on any one container, while the energization of the retaining relay retracts the rod element 178 and releases the container 150. The container 150 now proceeds along the conveying path until it clears the machine. With the relay unit set, the container closing device is also conditioned to perform another gathering and binding operation.

As a succeeding container proceeds along the conveying path, it contacts the lever 166 of the sensing switch 162 opening its circuit. This in turn causes the retaining means relay 160 to assume its reset position which de-energizes the retaining means solenoid 184, extends its rod element 178 and conditioning the securing means solenoid 74 to receive stimulation when the sensing switch 162 resumes its closed position. The machine then proceeds as before to gather and bind the end 152 of the container 150 after which the container 150 is released and the retaining means relay 160 is set for another operation.

The Figure 13 illustrates the top end 162 of a container 150 after it has been bound by a metal band 196.

The components of the electrical system of the closing device are interconnected by a cable 202.

Refer now to Figures 14, 14a and 14b which schematically illustrate the electrical system of the container closing device. The Figure 14 shows the system with its

switch 200 open, while Figure 14a illustrates the system conditioned for a closing operation after its switch 200 has been closed. The Figure 14b illustrates the condition of the system when a container unit 150 actuates the contact arm 208 of the sensing switch 162.

Power is delivered to the electrical system at the input terminals 204, 206. The drive motor 52 bridges the terminals 204, 206 through an on-off switch 200. The input terminal 204 is also joined to the contact arm 208 of the container sensing switch 162 when the on-off switch 200 is in its on position. The sensing switch 162 is normally in its closed position with its contact arm 208 engaging its contact element 210. The spring element 211 urges the arm 208 towards its position contacting element 210. The sensing switch 162 assumes its other or open position when the lever 166 is engaged by a container at which time the contact arm 208 engages the open contact element 212 of the switch 162.

The contact element 210 of the container sensing switch 162 is joined to the contact arm 214 of the retaining means relay 160. When the relay 160 is in its reset position, its contacts arm 214 engages its contact element 216, while when in its set position the contact arm 214 engages the contact element 218. The spring element 219 urges the arm 214 towards its position engaging the element 216. The relay actuating coil 220 has one lead connected to the contact element 218, while its other lead connects with the input terminal 206. The relay 160 assumes its reset position unless the actuating coil 220 is energized at which time it assumes its set position.

The contact element 216 of the container retaining means relay 160 is joined with the armature 222 of the set-up switch 78. The contact arm 222 of the set-up switch 78 normally engages its contact element 224, and momentarily engages its contact element 226 when it is actuated by the rotation of the cam wheel 76 during a stitching operation. The spring element 225 of switch 78 maintains its arm 22 in engagement with the cam wheel 76. The securing means solenoid 74 is bridged between the contact element 224 of the set-up switch 78 and the input terminal 206.

The contact elements 218 and 226, respectively of the retaining means relay 160 and the set-up switch 78 are joined together and returned by the retaining means solenoid 184 to the input terminal 206.

The schematic diagram of Figure 14 illustrates the electrical system of the container closing device with its on-off switch 200 in the off or open position. The container sensing switch 162 is in its closed or disengaged position, the sensing means relay 160 is in its reset or de-energized position, and the set-up switch 78 is in its normal position. The retaining means solenoid 184 under these circumstances is de-energized (so that the rod element 178 is extended) and the securing means solenoid 74 is also de-energized.

When the container closing device is ready for operation, the on-off switch 200 is placed in its on or closed position actuating the motor 52. This also results in the completion of the circuit through the sensing switch 162, sensing means relay 160, set-up switch 78 and the securing means solenoid 74. With the securing means solenoid 74 energized, the stitching head 56 is triggered to perform a stitching operation which results in the rotation of the cam wheel 76. The rotation of the cam wheel 76 opens the circuit to the securing means solenoid 74, de-energizing it. The stitching head 56, however, once triggered continues its operation until completed. As the cam wheel 75 continues rotating it causes the contact arm 222 to momentarily engage the contact element 226 of the set-up switch 78 as shown by the dashed lines in Figure 14a. This completes the circuit through the retaining means solenoid 184 energizing it (resulting in retraction of the rod element 178), while also activating the actuating coil 220 of the relay 160 causing it to assume its set position.

When the relay 160 assumes its set position, it maintains the retaining means solenoid 184 in its energized state and prevents the energization of the securing means relay 74 when the set-up switch 78 resumes its normal position upon the completion of the stitching operation by the head 56.

It is noted that the stitching operation, which is performed by the head 56 when the on-off switch 200 is first closed, does not enclose a container but is carried out to place the retaining means relay 160 in its set position and to condition the electrical system for operation.

With the electrical system thus conditioned, as shown in Figure 14a, with its retaining means relay 160 in its set position, containers may be fed to the conveying means of the container closing device. As a container 150 moves along the conveying path, its leading edge engages the sensing switch 162 and causes it to assume its open position. With the sensing switch 162 in its open position, the actuating coil 220 of the retaining means relay 160 is de-energized causing the relay to assume its reset position. The opening of the sensing switch 162 also de-energizes the retaining means solenoid 184 and extends the rod element 178. This condition of the system is illustrated by the Figure 14b.

As the container continues to move along its path, the sensing switch loses contact with the container at its trailing edge and reassumes its closed position. With the relay 160 now in its reset position, the securing means solenoid 74 is energized and the stitching head 56 is triggered. The container unit, which has now been gathered and positioned at its binding location opposite the stitching head, is bound by a wire band 196.

The set-up switch 78 which is actuated by the cam wheel 76 during the stitching operation, momentarily assumes its second position and delivers a signal to the retaining means relay 160, causing it to assume its set position. The relay 160 in its set position energizes the retaining means solenoid 184 causing retraction of its rod element 178 at the completion of the stitching operation. This allows the container 150 to proceed along the conveyor path away from the stitching position and out of the device.

The retaining means relay 160 is again in its set position (see Figure 14a) and the sensing switch 162 is prepared for actuation by the next container 150, for again repeating the enclosing operation which was just described.

The many advantages of this container closing device which can handle and treat many containers in a rapid and efficient manner, will be obvious to those skilled in the art. It is also noted that the set-up switch 78, besides setting the sensing means relay 160 with each closing operation, also acts to prevent the stitching head 56 from performing more than one closing operation upon each container 150. This is effected by de-energizing the securing means solenoid 74 before the completion of the stitching operation, thereby preventing the continued operation of the stitching head.

The Figure 15 discloses a modified form of the container closing device shown in Figure 1, whereby a bottom and side supporting conveyor 230 is provided for engaging the lower part of the container 150.

Whereas the device shown in Figure 1 is adapted to support the container 150 by solely engaging it at its top end portion 152, in the case of large containers or containers filled with heavy substances it may be of advantage to provide additional support for the container 150 at its lower extremity.

The bottom conveyor 230 is synchronized with the conveyor belts 108, 110 by utilizing a common drive motor 232. The machine shown in Figure 15 therefore differs from that shown in Figure 1 in that the motor 52 is no longer used to drive the conveyor belts 108, 110, but is used solely for actuating the stitching head 56.

A drive shaft 234 connects with the drum wheel 104 for actuating the conveyor belts 108, 110 and is coupled with

the drive shaft 240 of the bottom conveyor 230 by a pair of bevel gears 236 and a universal joint 238. The drive shaft 240 is provided with a pulley wheel 242 which is coupled by a link belt with a pulley wheel 244 joined with the shaft of the drive motor 232.

As already noted, the main frame unit 19 and block member 32 of the container closing device allows vertical position adjustment of the main conveyor means which engages the top portion of the container 150. This provides accommodation for different container sizes.

The vertical adjustment of the machine also greatly increases its adaptability, since it allows the container closing device to be used with various other conveyors and permits frequent changes from one conveyor to another.

While this invention has been disclosed in connection with several representative embodiments, there will be obvious to those skilled in the art that many additions and variations may be made in the structures without essentially departing from the spirit of the invention.

20. What is claimed is:

1. In a closure device, conveying means for directing a container along a predetermined path, and a retractable rod retaining means controllably extended for engaging and preventing the motion of said container along its path at a predetermined location, said conveying means continuously engaging and tending to move said container past said location.

2. In a closure device, conveying means for continuously directing a container along a predetermined conveying path by engaging the open end of said container, and retaining means controllably engaging the open end of said container and preventing its motion along said conveying path at a predetermined location, said conveying means continuously engaging and tending to move said open end past said location.

3. In a closure device, conveying means for continuously directing a bag container along a predetermined conveying path by engaging the open end of said container, and retaining means controllably engaging the open end of said container and preventing its motion past a predetermined location along its said conveying path, the open end of said container being gathered by the action of said conveying means tending to move said open end past said location.

4. In a closure device, conveying means for continuously directing a bag container along a predetermined path by engaging the open end of said container, and retaining means controllably extending to engage the open end of said container and prevent its motion past a predetermined location along the conveying path of said conveying means, the open end of said container being gathered by the action of said conveying means tending to move said container past said location.

5. In a closure device, conveying means for continuously directing a bag container along a predetermined path by engaging the flattened end of said container between its leading and trailing edges, and retaining means controllably extending to engage the flattened end of said container at its leading edge and prevent the conveying motion past a predetermined location along its path of said conveying means, the flattened end of said container being gathered by the action of said conveying means moving the trailing edge toward the leading edge of said container when the leading edge is engaged by said retaining means.

6. In a closure device, conveying means for continuously directing a bag container along a predetermined path comprising a gripping member traveling along said path adapted to frictionally engage one side of the flattened end of said bag container between its leading and trailing edges and a pressure plate extending along said path for slidably engaging the other side of the flattened end of said container, and retaining means controllably extending in the direction between the gripping member

and pressure plate of said conveying means to engage the flattened end of said container at its leading edge and prevent its motion past a predetermined location along the conveying path of said conveying means and gripping member, the flattened end of said container being gathered by the action of the gripping member of said conveying means moving the trailing edge toward the leading edge of said container when the leading edge is engaged by said retaining means.

7. In a closure device, conveying means for continuously directing a bag container along a predetermined path comprising an endless belt traveling along said path adapted to frictionally engage the first side of the flattened end of said bag container between its leading and trailing edges and a pressure plate extending along said path proximate said endless belt for slidably engaging the second side of the flattened end of said container and urging its first side against said endless belt, and a retaining element controllably extending between the endless belt and the pressure plate of said conveying means to engage the flattened end of said container at its leading edge and prevent its motion past a predetermined location along the conveying path of said conveying means and said belt, the flattened end of said container being gathered by the action of the endless belt of said conveying means moving the trailing edge toward the leading edge of said container when the leading edge is engaged by said retaining element.

8. In a closure device, conveying means for supporting and continuously directing a bag container along a predetermined path comprising a pair of endless belts traveling in parallel directions along said path both adapted to frictionally engage the first side of the flattened end of said bag container along parallel regions between its leading and trailing edges and a pressure plate extending along said path proximate said pair of endless belts for slidably engaging the second side of the flattened end of said container and urging its first side against said endless belts, and a retaining element controllably extending across said path in the direction between the endless belts and the pressure plate and intermediate the pair of endless belts of said conveying means to engage the flattened end of said container at its leading edge and prevent its motion past a predetermined location along the conveying path of said conveying means and said belt, the flattened end of said container being gathered by the action of the endless belts of said conveying means moving the trailing edge toward the leading edge of said container when the leading edge is engaged by said retaining element.

9. In a closing device, conveying means for supporting and continuously directing a bag container along a predetermined path comprising an endless belt traveling along said path provided with a vertical surface adapted to frictionally engage the first side of the flattened top end of said bag container between its leading and trailing edges and a pressure plate extending along said path having a vertical surface proximate said endless belt for slidably engaging the second side of the flattened top end of said container and urging its first side against said endless belt, and a retaining rod element controllably extending across said path below the endless belt of said conveying means to engage the flattened end of said container at its leading edge and hinder its motion past a predetermined location along the conveying path of said conveying means and said belt, the flattened top end of said container being gathered by the continuous action of the endless belt of said conveying means tending to move the trailing edge toward the leading edge of said container when the leading edge is engaged by said retaining rod element.

10. In a closing device, conveying means for supporting and continuously directing a bag container along a predetermined path comprising a pair of vertically spaced congruous endless belts synchronously traveling in parallel directions along said path both adapted to frictionally

engage the first side of the flattened top end of said bag container along vertically oriented parallel regions between its leading and trailing edges and a pressure plate extending along said path and having a vertical surface proximate said pair of endless belts for slidably engaging the second side of the flattened top end of said container and urging its first side against said endless belts, and a retaining rod element controllably extending across said path to engage the flattened end of said container at its leading edge intermediate the endless belts of said conveying means and prevent its motion past a predetermined location along the conveying path of said conveying means and said belts, the flattened top end of said container being gathered by the continuous action of the endless belts of said conveying means tending to move the trailing edge toward the leading edge of said container when the leading edge is engaged by said retaining rod element.

11. In a closing device, conveying means for directing a loaded container along a predetermined path comprising a gripping member traveling along said path adapted to frictionally engage one side of the end of said container, and a pressure plate with a vertical bearing surface extending along said path for slidably engaging the other side of the end of said container, and a supporting member urging said gripping member toward said pressure plate.

12. In a closing device, conveying means for directing a loaded container along a predetermined path comprising an endless belt traveling along said path adapted to frictionally engage the first side of the flattened end of said container between its leading and trailing edges and a pressure plate having a vertical bearing surface extending along said path proximate said endless belt for slidably engaging the second side of the flattened end of said container urging its first side against said endless belt to support the load of said container, and a supporting member slidably engaging said belt and urging said belt towards said pressure plate.

13. In a closing device, conveying means for supporting and directing a loaded bag container along a predetermined path comprising a pair of endless belts travelling in parallel directions along said path both having a front surface adapted to frictionally engage the first side of the flattened end of said bag container along parallel regions between its leading and trailing edges and a back surface, a pressure plate extending along said path proximate said pair of endless belts for slidably engaging the second side of the flattened end of said container and urging its first side against said endless belts to support the load of said container and urge it along said path, and a supporting member slidably engaging the back surface of at least one of said belts and maintaining its front surface directed toward said pressure plate for supporting the load of said container.

14. In a closing device, conveying means for supporting and directing a loaded bag container along a predetermined path comprising an endless belt traveling along said path provided with a vertical front surface adapted to frictionally engage the first side of the flattened top end of said bag container between its leading and trailing edges and a back surface, a pressure plate extending along said path having a vertical surface proximate the front surface of said endless belt for slidably engaging the second side of the flattened top end of said container and urging its first side against the vertical surface of said endless belt to support the load of said container and urge it along said path and a supporting member extending along said path having a vertical surface proximate the back surface of said endless belt for slidably engaging said back surface and maintaining the front surface of said belt directed towards said pressure plate.

15. In a closing device, conveying means for supporting and directing a loaded bag container along a predetermined path comprising an endless belt traveling along

said path provided with a vertical surface adapted to frictionally engage the first side of the flattened top end of said bag container between its leading and trailing edges and a bottom surface, a supporting member extending along said path and slidably engaging the bottom surface of said endless belt for maintaining its position under load conditions, and a pressure plate extending along said path having a vertical surface proximate said endless belt for slidably engaging the second side of the flattened top end of said container and urging its first side against the vertical surface of said endless belt to support the load of said container and urge it along said path.

16. In a closing device; conveying means for supporting and directing a bag container along a predetermined path, comprising a first endless belt traveling along said path provided with a vertical front surface adapted to frictionally engage the first side of the flattened top end of said bag container between its leading and trailing edges and a vertical back surface, a pressure plate extending along said path having a vertical surface proximate said endless belt for slidably engaging the second side of the flattened top end of said container and urging its first side against the vertical surface of said endless belt, a supporting member slidably engaging the back surface of said belt and maintaining its front surface directed towards said pressure plate, a second endless belt traveling along said path below said first endless belt provided with a substantially horizontal surface for carrying the bottom end of said bag container, and driving means synchronously motivating said first and second endless belts.

17. In a closing device, conveying means for directing a container having leading and trailing edges along a predetermined path by engaging the open end of said container, a sensing unit actuated by the passing of the leading and trailing edges of said container passing a fixed station along said path, and retaining means controlled by said sensing unit for conditionally interfering with the motion of the open end of said container along the conveying path of said conveying means at a predetermined location, said conveying means continuously engaging and tending to move the open end of said container past said location.

18. In a closing device, conveying means for directing a container having leading and trailing edges along a predetermined path by engaging the open end of said container, a sensing unit actuated by the leading and trailing edges of said container passing a fixed station along said path, and retaining means positioned along said path following said sensing unit for interfering with the motion of said container along the conveying path of said conveying means at a predetermined location, said sensing unit being actuated by the trailing edge of said container for terminating the interfering action of said retaining means.

19. In a closing device, conveying means for continuously directing a bag container along a predetermined path by engaging the flattened end of said container between its leading and trailing edges, a sensing unit actuated by the edges of said container passing a fixed station along its path, and retaining means positioned along said path following said sensing unit controlled by said sensing means to engage the flattened end of said container at its leading edge and prevent its motion past a predetermined location along the conveying path of said conveying means, the flattened end of said container being gathered by the action of said conveying means moving the trailing edge toward the leading edge of said container when the leading edge is engaged by said retaining means.

20. In a closing device, conveying means for continuously directing a bag container along a predetermined path comprising a gripping member traveling along said

path, adapted to frictionally engage one side of the flattened end of said bag container between its leading and trailing edges and a pressure plate extending along said path for slidably engaging the other side of the flattened end of said container retaining means controllably extending across said path to engage the flattened end of said container at its leading edge and prevent its motion past a predetermined location along the conveying path of said conveying means and said member, the flattened end of said container being gathered by the action of the gripping member of said conveying means moving the trailing edge toward the leading edge of said container when the leading edge is engaged by said retaining means, and a container sensing unit controlling said retaining means and positioned along said path preceding said retaining means, said retaining means being extended when said sensing unit is engaged by said container and retracted a predetermined time after said unit is not engaged by said container.

21. In a closing device, conveying means for continuously directing a bag container along a predetermined path comprising an endless belt traveling along said path adapted to frictionally engage the first side of the flattened end of said bag container between its leading and trailing edges and a pressure plate extending along said path proximate said endless belt for slidably engaging the second side of the flattened end of said container and urging its first side against said endless belt, a retaining means comprising a rod element and a solenoid controllably extending the rod element across said path to engage the flattened end of said container at its leading edge and prevent its motion past a predetermined location along the conveying path of said conveying means, and said belt, the flattened end of said container being gathered by the action of said endless belt of said conveying means moving the trailing edge toward the leading edge of said container when the leading edge is engaged by said retaining element, and a container sensing unit controlling said retaining means positioned along said path preceding said retaining means comprising an extending lever for contacting said container along its path, the solenoid of said retaining means being de-energized to extend its rod element only when the lever of said sensing unit contacts said container and remains de-energized for a predetermined time after it loses contact with said container.

22. In a closing device; conveying means for supporting and continuously directing a bag container along a predetermined path comprising a pair of endless belts traveling in parallel directions along said path both adapted to frictionally engage the first side of the flattened end of said bag container along parallel regions between its leading and trailing edges, and a pressure plate extending along said path proximate said pair of endless belts for slidably engaging the second side of the flattened end of said container and urging its first side against said endless belts; retaining means comprising a rod element, a solenoid for retracting and a spring for extending the rod element across said path intermediate the pair of endless belts of said conveying means to engage the flattened end of said container at its leading edge and prevent its motion past a predetermined location along its path, the flattened end of said container being gathered by the action of the endless belts of said conveying means moving the trailing edge toward the leading edge of said container when the leading edge is engaged by the rod element of said retaining means; and a container sensing unit positioned along said path preceding said retaining means comprising a switch normally closed to energize the solenoid of said retaining means retracting its rod element and an extending lever opening said switch to extend said rod element when contacting said container as it passes a fixed station along its path.

23. A closing device comprising conveying means for directing a container along a predetermined path, a retractable rod retaining means controllably extended for engaging said container along its path at a predetermined location, and securing means for binding said container at said location, said conveying means gathering said container by continuously engaging and tending to move said container past said location.

24. A closing device comprising conveying means for directing a container along a predetermined path by engaging the open end of said container, retaining means controllably engaging the open end of said container and preventing its motion along the conveying path of said conveying means at a predetermined location, said conveying means continuously engaging and tending to move the open end of said container past said location, and securing means for binding said container at said location.

25. A closing device comprising conveying means for continuously directing a bag container along a predetermined path by engaging the open end of said container, retaining means controllably engaging and coacting with said conveying means for gathering the open end of said container by preventing its motion past a predetermined location along the conveying path of said conveying means, and securing means for binding the gathered end of said container.

26. A closing device comprising conveying means for continuously directing a bag container along a predetermined path by engaging the open end of said container, retaining means controllably extending to engage the open end of said container and prevent the conveying motion past a predetermined location along its path of said conveying means, the open end of said container being gathered by the action of said conveying means tending to move said container past said location, and securing means binding the gathered end of said container at said location.

27. A closing device comprising conveying means for continuously directing a bag container along a predetermined path by engaging the flattened end of said container between its leading and trailing edges, retaining means controllably extending to engage the flattened end of said container at its leading edge and preventing its motion past a predetermined location along the conveying path of said conveying means, the flattened end of said container being gathered by the action of said conveying means moving the trailing edge toward the leading edge of said container when the leading edge is engaged by said retaining means, and securing means for binding the gathered end of said container at said location.

28. A closing device comprising conveying means for directing a container along a predetermined path by engaging the open end of said container, retaining means controllably engaging said container along the conveying path of said conveying means at a predetermined location, said conveying means continuously engaging and tending to move the open end of said container past said location, securing means for binding said container at said location, and a sensing unit actuated by said container passing a station along said path preceding said location to control said retaining and securing means.

29. A closing device comprising conveying means for continuously directing a bag container along a predetermined path by engaging the open end of said container, retaining means controllably engaging the open end of said container and preventing its motion past a predetermined location along the conveying path of said conveying means, the open end of said container being gathered by the continuous action of said conveying means tending to move said open end past said location, securing means for binding the open end of said container, and a sensing unit actuated by said container passing a station along said path preceding said location controlling the retaining and securing means.

30. A closing device comprising conveying means for continuously directing a bag container having leading and trailing edges along a predetermined path, retaining means controllably extending to engage the leading edge of said container and prevent its motion past a predetermined location along its path, the container being gathered by the action of said conveying means moving the trailing edge toward the leading edge of said container when the leading edge is engaged by said retaining means, securing means for binding the gathered end of said container at said location, and a sensing unit actuated by the edges of said container passing a station along said path preceding said location controlling said retaining and securing means, said securing means being activated and said retaining means being retracted when said sensing unit is actuated by the trailing edge of said container.

31. A closing device comprising conveying means for continuously directing a bag container along a predetermined path by engaging the flattened end of said container between its leading and trailing edges, retaining means controllably extending to engage the flattened end of said container at its leading edge and preventing its motion past a predetermined binding location along its path, the flattened end of said container being gathered by the action of said conveying means moving the trailing edge toward the leading edge of said container when the leading edge is engaged by said retaining means, securing means for binding the gathered end of said container at said location, and a sensing unit actuated by the edges of said container passing a station along said path preceding said binding location, said retaining means being extended when said sensing unit is actuated by the leading edge of said container while said securing means is activated and said retaining means is retracted when said sensing unit is actuated by the trailing edge of said container.

32. A closing device comprising conveying means for continuously directing a bag container along a predetermined path including a gripping member traveling along said path adapted to frictionally engage one side of the flattened end of said bag container between its leading and trailing edges and a pressure plate extending along said path for slidably engaging the other side of the flattened end of said container, retaining means controllably extending across said path to engage the flattened end of said container at its leading edge and prevent its motion past a predetermined binding location along its path, the flattened end of said container being gathered by the action of the gripping member of said conveying means moving the trailing edge toward the leading edge of said container when the leading edge of said container is engaged by said retaining means, a triggered securing means for binding the gathered end of said container at said location, and a container sensing unit comprising an extending lever actuated by the edges of the container passing a station along said path preceding said binding location, said retaining means being extended when the lever of said sensing unit is actuated by the leading edge of said container while said securing means is activated and said retaining means is retracted when said sensing unit is actuated by the trailing edge of said container.

33. A closing device comprising conveying means for continuously directing a bag container along a predetermined path including an endless belt traveling along said path adapted to frictionally engage the first side of the flattened end of said bag container between its leading and trailing edges, and a pressure plate extending along said path proximate said endless belt for slidably engaging the second side of the flattened end of said container and urging its first side against said endless belt; retaining means comprising a rod element, and a solenoid controllably extending the rod element across said path to engage the flattened end of said container at its leading edge and prevent its motion past a predetermined bind-

ing location along its path; the flattened end of said container being gathered by the action of said endless belt of said conveying means moving the trailing edge toward the leading edge of said container when the leading edge is engaged by said retaining element; securing means comprising a stitching machine and a solenoid for triggering said stitching machine to bind the gathered end of said container at said binding location; and a container sensing unit controlling said retainer and securing means positioned along said path preceding said binding location comprising an extending lever for contacting said container along its path; the solenoid of said retaining means being de-energized to extend its rod element only when the lever of said sensing unit contacts said container; the solenoid of said securing means triggering said stitching machine for a single binding operation when the lever of said sensing unit loses contact with said container; the solenoid of said retaining means being energized to retract its rod element after each stitching operation.

34. A closing device comprising conveying means for supporting and continuously directing a bag container along a predetermined path including a pair of endless belts traveling in parallel directions along said path both adapted to frictionally engage the first side of the flattened end of said bag container along parallel regions between its leading and trailing edges, and a pressure plate extending along said path proximate said pair of endless belts for slidably engaging the second side of the flattened end of said container and urging its first side against said endless belts; retaining means comprising a rod element, and a solenoid for retracting and a spring for extending the rod element across said path intermediate the pair of endless belts of said conveying means to engage the flattened end of said container at its leading edge and preventing its motion past a predetermined binding location along its path; the flattened end of said container being gathered by the action of the endless belts of said conveying means moving the trailing edge toward the leading edge of said container when the leading edge is engaged by the rod element of said retaining means; securing means comprising a wire stitching machine having a clinching member positioned transverse said path at said binding location for binding the gathered end of said container, a single stitch clutch, a cam wheel revolving with each stitch of the machine, and a solenoid for triggering the clutch of said stitching machine; a set-up switch actuated by the cam wheel of said stitching machine with each stitching operation to deliver a signal pulse for energizing the solenoid of said retaining means to retract its rod element; and a container sensing unit comprising a normally closed circuit switch positioned along said path preceding said binding location having a lever extending proximate the clinching member of said securing means for contacting said container at its leading edge to open the circuit and reset the relay unit de-energizing the solenoid of said retaining means to extend its rod element, and losing contact at its trailing edge closing the circuit and delivering a signal through the reset relay to energize the triggering solenoid of said securing means causing the stitching machine to bind said container after which the rod element of said retaining means is retracted releasing said container and allowing it to proceed along its said path.

35. A closing device comprising conveying means for supporting and continuously directing a bag container along a predetermined path including a pair of endless belts traveling in parallel directions along said path both having vertical surfaces adapted to frictionally engage the first side of the flattened end of said bag container along parallel regions between its leading and trailing edges, and a pressure plate extending along said path having a vertical surface proximate the vertical surfaces of said pair of endless belts for slidably engaging the second side of the flattened end of said container and urging its first side against the vertical surfaces of said endless belts; retaining means comprising a rod element, a solenoid for retracting and a spring for extending the rod element across said path intermediate the pair of

75

endless belts of said conveying means to engage the flattened end of said container at its leading edge and preventing its motion past a predetermined binding location along its path, and a relay unit for energizing said solenoid; the flattened end of said container being gathered by the action of the endless belts of said conveying means moving the trailing edge toward the leading edge of said container when the leading edge is engaged by the rod element of said retaining means; securing means comprising a wire stitching machine having a clinching member positioned transverse said path at said binding location for binding the gathered end of said container, a single stitch clutch, a cam wheel revolving with each stitch of the machine, and a solenoid for triggering the clutch of said stitching machine to perform a stitch operation; a set-up switch actuated by the cam wheel of said stitching machine with each stitching operation to de-energize the triggering solenoid of said securing means and deliver a signal pulse to the relay unit setting it to energize the solenoid of said retaining means for retracting its rod element; and a container sensing unit comprising a normally closed circuit switch positioned along said path preceding said binding location having a lever extending proximate the clinching member of said securing means for contacting said container at its leading edge to open the circuit and reset the relay unit de-energizing the solenoid of said retaining means to extend its rod element, and losing contact at its trailing edge closing the circuit and delivering a signal through the reset relay to energize the triggering solenoid of said securing means causing the stitching machine to bind said container after which the rod element of said retaining means is retracted releasing said container and allowing it to proceed along its said path.

36. In a closing device directing a container having leading and trailing edges along a predetermined path, retaining means comprising a rod element and a solenoid controllably extending the rod element across said path to engage said container at its leading edge and prevent its motion past a predetermined location along its path, and a container sensing unit controlling said retaining means positioned along said path preceding said retaining means comprising an extending lever for contacting said container along its path, the solenoid of said retaining means being de-energized to extend its rod element only when the lever of said sensing unit contacts said container.

37. In a closing device directing a container having leading and trailing edges along a predetermined path; retaining means comprising a rod element, a solenoid for retracting and a spring for extending the rod element across said path to engage said container at its leading edge and prevent its motion past a predetermined location along its path; and a container sensing unit positioned along said path preceding said retaining means comprising a switch normally closed to energize the solenoid of said retaining means retracting its rod element and an extending lever opening said switch to extend said rod element when contacting said container as it passes a fixed station along its path.

38. In a closing device directing a container having leading and trailing edges along a predetermined path, retaining means controllably extending to engage the leading edge of said container and prevent its motion past a predetermined location along its path, securing means for binding said container at said location, and a sensing unit actuated by the edges of said container passing a station along said path preceding said location controlling said retaining and securing means, said securing means being activated and said retaining means being retracted when said sensing unit is activated by the trailing edge of said container.

39. In a closing device directing a container having leading and trailing edges along a predetermined path, retaining means controllably extending to engage said container at its leading edge and preventing its motion

past a predetermined binding location along its path, securing means for binding said container at said location, and a sensing unit actuated by the edges of said container passing a station along said path preceding said binding location, said retaining means being extended when said sensing unit is actuated by the leading edge of said container while said securing means is activated and said retaining means is retracted when said sensing unit is actuated by the trailing edge of said container.

40. In a closing device directing a container having leading and trailing edges along a predetermined path, retaining means controllably extending across said path to engage said container at its leading edge and prevent its motion past a predetermined binding location along its path, a triggered securing means for binding said container at said location, and a container sensing unit comprising an extending lever actuated by the edges of the container passing a station along said path preceding said binding location, said retaining means being extended when the lever of said sensing unit is actuated by the leading edge of said container while said securing means is activated and said retaining means is retracted when said sensing unit is actuated by the trailing edge of said container.

41. In a closing device directing a container having leading and trailing edges along a predetermined path; retaining means comprising a rod element, and a solenoid controllably extending the rod element across said path to engage said container at its leading edge and prevent its motion past a predetermined binding location along its path; securing means comprising a stitching machine, and a solenoid for triggering said stitching machine to bind said container at said binding location; and a container sensing unit controlling said retainer and securing means positioned along said path preceding said binding location comprising an extending lever for contacting said container along its path; the solenoid of said retaining means being de-energized to extend its rod element only when the lever of said sensing unit contacts said container; the solenoid of said securing means triggering said stitching machine for a single binding operation when the lever of said sensing unit loses contact with said container; the solenoid of said retaining means being energized to retract its rod element after each stitching operation.

42. In a closing device directing a container having leading and trailing edges along a predetermined path; retaining means comprising a rod element, and a solenoid for retracting and a spring for extending the rod element across said path to engage said container at its leading edge and preventing its motion past a predetermined binding location along its path; securing means comprising a wire stitching machine having a clinching member positioned transverse said path at said binding location for binding said container, a single stitch clutch, a cam wheel revolving with each stitch of the machine, and a solenoid for triggering the clutch of said stitching machine; a set-up switch actuated by the cam wheel of said stitching machine with each stitching operation to deliver a signal pulse for energizing the solenoid of said retaining means to retract its rod element; and a container sensing unit comprising a normally closed circuit switch positioned along said path preceding said binding location having a lever extending proximate the clinching member of said securing means for contacting said container at its leading edge to open the circuit, and losing contact at its trailing edge to close said circuit; said sensing unit de-energizing the solenoid of said retaining means extending its rod element when its circuit is opened; said sensing unit energizing the solenoid of said securing means to trigger said stitching machine for one operation.

43. In a closing device directing a container having leading and trailing edges along a predetermined path; retaining means comprising a rod element, a solenoid for retracting and a spring for extending the rod element across said path to engage said container at its leading

edge and preventing its motion past a predetermined binding location along its path, and a relay unit for energizing said solenoid; securing means comprising a wire stitching machine having a clinching member positioned transverse said path at said binding location for binding said container, a single stitch clutch, a cam wheel revolving with each stitch of the machine, and a solenoid for triggering the clutch of said stitching machine to perform a stitch operation; a set-up switch actuated by the cam wheel of said stitching machine with each stitching operation to de-energize the triggering solenoid of said securing means and deliver a single pulse to the relay unit setting it to energize the solenoid of said retaining means for retracting its rod element; and a container sensing unit comprising a normally closed circuit switch positioned along said path preceding said binding location having a lever extending proximate the clinching member of said securing means for contacting said container at its leading edge to open the circuit and reset the relay unit de-energizing the solenoid of said retaining means to extend its rod element, and losing contact at its trailing edge closing the circuit and delivering a signal through said relay in its reset position to energize the triggering solenoid of said securing means causing the stitching machine to bind said container after which the rod element of said retaining means is retracted releasing said container and allowing it to proceed along its path.

44. In a closing device directing a container along a predetermined path, stitching means for binding said container by a single action, and an electrical switch sensing unit actuated by engagement with said container passing a station along said path and triggering said stitching means upon disengagement with said container.

45. In a closing device directing a container having leading and trailing edges along a predetermined path, securing means for binding said container at a predetermined location along said path by a single action, and a sensing unit actuated by the trailing edge of said container passing a station along said path preceding said location to activate said securing means.

46. In a closing device directing a container having leading and trailing edges along a predetermined path, securing means for binding said container at a predetermined location along its path, and an electrical switch sensing unit actuated by the edges of said container passing a station along said path preceding said location controlling said securing means, said securing means being actuated by the trailing edge of said container.

47. In a closing device directing a container having leading and trailing edges along a predetermined path, a triggered securing means for binding said container at a predetermined location along said path, and an electrical switch sensing unit comprising an extended lever actuated by the edges of said container passing a station along said path preceding said binding location, said securing means being activated when said sensing unit is actuated by the trailing edge of said container.

48. In a closing device directing a container having leading and trailing edges along a predetermined path; securing means comprising a stitching machine, and a solenoid for triggering said stitching machine to bind said container at a predetermined location along said path; and a container sensing unit controlling said securing means positioned along said path preceding said binding location actuated by the leading and trailing edges of said container passing along said path; the solenoid of said securing means triggering said stitching machine for a single binding operation when said sensing unit is actuated by the trailing edge of said container.

49. In a closing device directing a container having leading and trailing edges along a predetermined path; securing means comprising a wire stitching machine having a clinching member positioned transverse said path at a predetermined location for binding said container, a single stitch clutch, a cam wheel revolving with each

stitch of the machine, and a solenoid for triggering the clutch of said stitching machine to perform a stitch operation; a set-up switch actuated by the cam wheel of said stitching machine with each stitching operation to de-energize the triggering solenoid of said securing means and deliver a signal pulse; a container sensing unit comprising a normally closed circuit switch positioned along said path preceding said binding location having a lever extending proximate the clinching member of said securing means for contacting said container to open the circuit, and losing contact with said container to close said circuit; and a relay unit set up by a signal from said set-up switch and reset when the switch of said sensing unit is actuated to its open circuit position; said sensing unit energizing the solenoid of said securing means to trigger said stitching machine for one operation only when said relay unit is in its reset position.

50. In a closing device, an electrical circuit comprising a container sensing unit having first and second states assumed respectively in the absence of a sensed container and upon sensing a container, a conditioned switching unit having first and second states and receiving a signal from said sensing unit when said sensing unit is in its first state, a set-up unit having first and second states and receiving signals from said conditioned unit, and an output line conditionally energized by said set-up unit for activating a container securing means, said sensing unit when in its first state delivering a signal to said output line when said conditioned unit and said set-up unit are in their first states, said set-up unit when in its second state delivering said signal from said sensing unit to said conditioned unit wherein said conditioned unit is set to its second state preventing the delivery of a signal from said sensing unit for delivery by said set-up unit to said output line.

51. The electrical circuit of claim 50 wherein said conditioned unit is set to its second state upon receiving said signal from said set-up unit and is maintained in its second state by receipt of said signal from said sensing unit in its first state.

52. The electrical circuit of claim 51 wherein said conditioned unit is maintained in its second state by receipt of a signal from said sensing unit in its first state until said conditioned unit is reset to its first state when said sensing unit is actuated to its second state by sensing a container, whereupon the electrical circuit is conditioned to deliver a signal to said output line when said sensing unit assumes its first state upon removal of said sensed container.

53. In a closing device, an electrical circuit comprising a container sensing switch unit having a first disengaged state and a second engaged state assumed respectively in the absence of a sensed container and upon sensing a container, a relay unit having a first de-energized state and a second energized state and receiving a signal from said sensing unit when said sensing unit is in its disengaged state, a set-up switch unit receiving a signal from said relay unit and having first and second states, and an output line conditionally energized by said set-up switch unit for activating a container securing means, said sensing switch unit when in its disengaged state delivering a signal to said output line when said relay unit and said set-up switch are in their first states, said set-up switch unit when in its second state delivering said signal from said sensing unit to said relay unit setting said relay unit to its energized state, said relay unit being reset to its first state when the sensing unit is actuated to its engaged state by sensing a container.

54. The electrical circuit of claim 53 wherein said set-up switch unit momentarily assumes its second state to place said relay unit in its energized state after said output line receives said signal, said relay unit being thereafter maintained in its energized state by receipt of said signal from said sensing switch unit in its first dis-

engaged state until said sensing switch unit assumes its second state by sensing a container.

55. In a closing device, an electrical circuit comprising a container sensing switch unit having a first disengaged state and a second engaged state assumed respectively in the absence of a sensed container and upon sensing a container, a relay unit having a first de-energized state and a second energized state and receiving a signal from said switch unit in its disengaged state, a set-up switch unit receiving a signal from said relay unit and having first and second states, a first output line conditionally energized by said set-up switch unit for activating a container securing means, and a second output line conditionally energized by said relay unit for controlling the retention of a container along a conveying path, said sensing switch unit when in its disengaged state delivering a signal to said first output line for activating said container securing means when said relay unit and said set-up switch are in their first states, said set-up switch unit when in its second state delivering said signal from said sensing switch unit to said relay unit setting said relay to its energized state for releasing said container along said conveying path, said set-up switch unit momentarily assuming its second state for setting said relay to its energized state after said first output line receives said signal, said relay unit in its second state delivering the signal from said sensing switch unit to said second output line for activating said securing means, said relay unit being reset to its first state when said sensing switch unit is actuated to its engaged state by sensing a container.

56. In a closing device, an electrical circuit comprising a securing means solenoid for actuating a container securing means, a retaining means solenoid for controlling the retention of a container along a conveying path, a container sensing switch unit having closed and open positions assumed respectively upon failing to sense and upon sensing a said container, a set-up switch unit having first and second positions assumed respectively for engaging said securing means solenoid and said retaining means solenoid, and a retaining means relay unit having set and reset positions controlling said retaining means solenoid, said container sensing switch unit when in its closed position and said relay unit is in its reset position delivering a signal to said set-up switch unit, said set-up switch unit when in its first position delivering said signal from said sensing switch unit to said securing means solenoid for energizing said securing means and when in its second position delivering said signal to said relay unit setting said relay unit, said set-up switch unit momentarily assuming its second position after said securing means solenoid receives said signal, said relay unit in its set position delivering the signal from said sensing switch unit to said retaining means solenoid, said relay unit being reset when said sensing switch unit is actuated to its open position by sensing a container.

57. In a closing device; a securing means comprising a wire stitching machine, a single stitch clutch for driving said machine, a cam wheel revolving with each stitch of the machine, and a solenoid for triggering the clutch of said stitching machine to perform a stitch operation; a retaining means comprising a solenoid, and a relay unit having set and reset positions; a container sensing unit comprising a normally closed switch having an open contact position; a set-up switch unit having a first normal position and a second position; the switch of said container sensing unit when in its closed position with the relay unit of said retaining means in its reset position delivers a signal to said set-up switch unit; said set-up switch unit when in its first position delivering said signal from the switch of said sensing unit to the solenoid of said securing means triggering its clutch to perform a stitch operation and revolve its cam wheel; said set-up switch momentarily assuming its second position by actuation of the cam wheel of said securing means to deliver said signal from said sensing unit to said retaining

means setting its relay unit; the relay unit of said retaining means in its set position delivering the signal from the switch of said sensing unit to the solenoid of said retaining means; the relay unit of said retaining means being reset when the switch of said sensing unit is actuated to its open position.

58. In a closing device; an electrical system comprising an input terminal for receiving energization; a container sensing switch having first and second contact elements, and a contact arm connected with said input terminal and normally engaging the first contact element and engaging the second contact element upon sensing a container; a relay unit having first and second contact elements, an actuating coil connected with the second contact element, and a contact arm connected with the first contact element of said first switch and engaging the second contact element when the actuating coil is energized; and a set-up switch having a first contact element for delivering a signal for actuating a container securing means, a second contact element connected to the second contact element of said relay unit for energizing the actuating coil of said relay unit, and a contact arm connected with the first contact element of said relay unit and normally engaging the first contact element.

59. In a closing device; an electrical circuit comprising an input terminal for receiving energization; an output line for delivering a signal for actuating a container securing means; a container sensing switch having first and second contact elements, and a contact arm connected with said input terminal and normally engaging the first contact element in the absence of a container and engaging the second contact element upon sensing a container; a retaining means relay unit having first and second contact elements, an actuating coil connected with the second contact element, and a contact arm connected with the first contact element of said sensing switch and engaging the second contact element when the actuating coil is energized; and a set-up switch having a first contact element connected with said output line, a second contact element connected to the second contact element of said relay unit for energizing the actuating coil of said relay unit, and a contact arm connected with the first contact element of said relay unit normally engaging the first contact element and momentarily contacting its second contact element when said output line receives a signal for energizing the actuating coil of said relay unit.

60. In a closing device; an electrical circuit comprising an input terminal; a securing means solenoid for actuating a container securing means; a retaining means solenoid for controlling the retention of a container along a conveying path; a container sensing switch having first and second contact elements, and a contact arm connected with said input terminal and normally engaging the first contact element in the absence of a container and engaging the

second contact element upon sensing a container; a retaining means relay unit having a first contact element, a second contact element connected with said retaining means solenoid, an actuating coil connected with the second contact element, and a contact arm connected with the first contact element of said sensing switch and engaging the second contact element and energizing said retaining means solenoid when the actuating coil is energized; and a set-up switch having a first contact element connected with said securing means solenoid, a second contact element connected to the second contact element of said relay unit, and a contact arm connected with the first contact element of said relay unit normally engaging the first contact element for delivering an energizing signal to said securing means solenoid and momentarily contacting its second contact element for energizing the actuating coil of said relay unit when said securing means solenoid is energized.

61. In a closing device; an input terminal; a securing means comprising a wire stitching machine, a single stitch clutch for driving said machine, a cam wheel revolving with each stitch of the machine, and a solenoid for triggering the clutch of said stitching machine to perform a stitch operation; a retaining means solenoid, a container sensing switch having first and second contact elements, and a contact arm connected with said input terminal and normally engaging the first contact element; a retaining means relay unit having a first contact element, a second contact element connected with said retaining means solenoid, an actuating coil connected with the second contact element, and a contact arm connected with the first contact element of said sensing switch and engaging the second contact element when the actuating coil is energized; and a set-up switch having a first contact element connected with said securing means solenoid, a second contact element connected to the second contact element of said relay unit, and a contact arm connected with the first contact element of said relay unit normally engaging the first contact element and actuated by the cam wheel of said securing means to momentarily contact its second contact element when said securing means solenoid is energized and said stitching machine performs a stitch operation.
